Atty.

UNITED STATES PATENT OFFICE.

ARCHILL J. LE CLAIR, OF HAVERHILL, MASSACHUSETTS.

WELT-INNERSOLE.

1,264,663.

Specification of Letters Patent. Patented Apr. 30, 1918.

Application filed February 18, 1918. Serial No. 217,812.

To all whom it may concern:

Be it known that I, ARCHILL J. LE CLAIR, a citizen of the United States, and a resident of Haverhill, in the county of Essex and State of Massachusetts, have invented 5 an Improvement in Welt-Innersoles, of which the following is a specification.

This invention particularly relates to certain improvements on the welt innersole 10 shown in my prior patent Serial No. 1,222,309, dated April 10, 1917.

In the inner sole of my said prior patent, the textile strip which was attached to the outer or bottom section of the sole, was not 15 of sufficient strength to meet all conditions or requirements, and the lip also did not offer sufficient resistance to the guiding devices of the welter to satisfy the operator. Certain difficulties were also encountered in 20 shaping the lip into its upstanding position.

The objects of my present invention are to increase the strength and durability of the parts which hold the shoe in shape, to 25 form the lip to which the upper is attached so that its stiffness will be greatly increased, thereby enabling it to resist the pressure of the guiding devices of the welter thereagainst to the desired extent, and to 30 improve the methods of making the innersole, so that the facility with which it may be manufactured may be substantially increased.

I accomplish these objects by the means 35 shown in the accompanying drawing, in which:

Figure 1 is a bottom plan view of a welt innersole, embodying my invention.

Fig. 2 is a transverse sectional view there- 40 of on line 2-2 of Fig. 1.

Figs. 3 to 5 are detail sectional views taken on an enlarged scale, illustrating different steps in the process of manufacture.

As shown in the drawing, the innersole 45 comprises an inner section *a* of complete sole shape and an outer section *b*, of similar shape about the heel, but reduced in size about the shank and fore-part by slightly more than the width of the usual 50 margin between the sole edge and the lip; a textile covering *c* being adhesively connected to the outer surface of the outer section, and the two sections being adhesively connected and preferably formed of some 55 inexpensive material, as leather board, as described in my said prior patent.

According to my present invention, a strip of tape *d*, of stout textile material, is provided, which is of sufficient length to extend throughout the reduced shank and fore-part portions of said outer section and is attached thereto, said strip being folded so that it is three-ply, one edge portion being doubled in between the other edge portion and the middle portion. 60

The method which I employ in making the inner sole is as follows: The tape, folded as above described, is first attached to the outer section *b*, to which the textile covering has been previously attached, by 65 placing one edge portion *x* of the tape on the inner side of said section *b*, or side which is to lie next the inner section *a*, and the doubled opposite edge and middle portions *g* and *z* on the opposite side there- 70 of, to which the textile covering *c* is attached, and by sewing the same through and through by stitches *e*, which extend perpendicularly to the outer section *b*, through all of said portions of the tape and said section and covering *c* adjacent the edges thereof, as indicated in Fig. 3. As shown in 75 this figure, the tape will then be in the plane of the sole section, at this stage of the operation, and provides a flexible lip which projects beyond the edge of the sole section. A flexible lip is thus formed on the 80 edge of the sole section *b*, which is then bent about the edge thereof, toward its outer side, into a position approximately 85 perpendicular to its outer surface.

This step in the operation is performed, and the lip is secured in an upright position by pressing the lip into this position by hand, and then holding it in this position 90 by pressing the edge of the sole section against the bed of a sewing machine, as indicated in Fig. 4, and sewing the tape portions *x*, *g*, and *z* together by stitches *f*, which pass therethrough perpendicularly to the 95 stitches *e*, or in a direction parallel to the surface of the sole section, as indicated in Fig. 5. In practice the lip is turned up as it is fed to the sewing mechanism so that the operation may be rapidly performed on 100 an ordinary cylindrical table sewing machine. The lip thus upturned will be held in upturned position by the stitches *f* for the following reason. When the lip is turned up, as above described, the relative 105 positions of the sections of the material are changed, one sliding over the other, so that

the outer section *a* will be somewhat shorter than the inner section *a* with relation to the row of stitches *e*, and these tape portions will be fastened, one on the other, by the 5 stitches *f*, while thus held, so that they will be prevented from sliding back, one on the other, to their original relative positions, when released. The edge portion *a* thus acts to support the lip in upright position, for, 10 to bend the lip back to the horizontal position would tend to compress the portion thereof between the stitches *e* and *f* which extend about the edge of the sole section *b*.

As a result, an upstanding lip will be 15 formed which is of sufficient strength and stiffness to resist effectively the force with which it is pressed against the guiding devices of the welter when the shoe is welted, so that the conditions encountered by the 20 operator are no different than with the ordinary "Gem" innersole, or similar innersoles which have previously been extensively employed. Moreover, a particularly strong lip is provided by this construction, as it is 25 three-ply, so that it will be of sufficient strength to meet all conditions, and a "non-stretchable" innersole will be produced.

After the lip has been attached and upturned, as indicated in Fig. 5, the innersole 30 section *a* is adhesively attached to the outer section *b*, as in my said prior patent.

I claim:—

1. A welt innersole comprising a sole shaped inner section, an outer section connected thereto and having the edge of its shank and fore-part portions disposed at a substantial distance within the corresponding portions of the inner section, a lip of textile material comprising two longitudinally extending portions attached, adjacent the edges thereof, to opposite sides of the edge portions of said outer section and bent to extend therefrom transversely of the plane thereof, and means for attaching said 45 portions together beyond the edge of said outer section to hold them in said bent position.

2. A welt innersole comprising a sole shaped inner section, an outer section connected thereto and having the edge of its shank and fore-part portions disposed at a substantial distance within the corresponding 50 portions of the inner section, a lip comprising a strip of textile material folded longitudinally and arranged with its edge

portions at opposite sides of the said edge portions of said outer section, and stitched thereto, said strip extending laterally beyond the edge of said outer section and bent outwardly therefrom at approximately right 60 angles thereto and having said extending portions stitched together, the stitches which attach the strip to the sole section and those which attach the strip portions together being disposed at approximately right angles 65 to each other.

3. A welt innersole comprising a sole shaped inner section, an outer section connected thereto and having the edge of its shank and fore-part portions disposed at a 70 substantial distance within the corresponding portion of the inner section, and a strip of textile material longitudinally folded and arranged astride, and with its edge-portions overlapping and stitched to the edge portions of said outer section, the edge portion of said strip, extending from between said sole sections, being bent across the edge of the outer section and the opposite edge portion thereof being bent in the same direction, 75 said edge portions being stitched together adjacent said outer section to provide a permanently outwardly projecting lip.

4. A welt innersole comprising a sole shaped inner section, an outer section connected thereto and having the edge of its shank and fore-part portions disposed at a 80 substantial distance within the corresponding portion of the inner section, and a strip of textile material longitudinally folded, so 85 that one edge portion is disposed between the other edge portion and the intermediate portion thereof, said strip being stitched to the edge portion of said outer section with one of its said edge portions at one side of, and 90 adjacent the said edge of said outer section and the other edge portion and the intermediate portion at the opposite side thereof, to 95 form a lip arranged to extend beyond the edge of said outer section, said lip being 100 bent away from the inner section at a sharp angle, to project beyond the outer surface of the outer section, the projecting portions of the strip forming said lip being secured together in bent position by stitches passing 105 therethrough beyond the said edge of the outer section.

In testimony whereof, I have signed my name to this specification.

ARCHILL J. LE CLAIR.
